Primary Examiner—Brian N. Vinson**Attorney, Agent, or Firm—Richard C. Litman****[57]****CLAIM**

The ornamental design for a ribbon dispenser, as shown and described.

DESCRIPTION

FIG. 1 is a top, front, and right side perspective view of a ribbon dispenser showing my new design;

FIG. 2 is an enlarged front elevational view thereof, the rear being plain and unornamented;

FIG. 3 is an enlarged top plan view thereof;

FIG. 4 is an enlarged right side elevational view thereof; and,

FIG. 5 is an enlarged left side elevational view thereof. The broken line disclosure of ribbon rolls in the views is for illustrative purposes only and forms no part of the claimed design. The dispenser is shown broken-away in the views to indicate indeterminate width.
